UNITED STATES PATENT OFFICE.

CHESTER H. TEEGARDEN, OF WASHINGTON, DISTRICT OF COLUMBIA.

METHOD OF RECEIVING TELEGRAPH-SIGNALS.

1,346,614.

Specification of Letters Patent. Patented July 13, 1920.

Application filed September 9, 1918. Serial No. 253,308.

To all whom it may concern:

Be it known that I, CHESTER H. TEEGARDEN, a citizen of the United States, residing at Washington, in the District of Columbia, have invented certain new and useful Improvements in Methods of Receiving Telegraph-Signals, of which the following is a specification.

My invention relates to telegraphy and more particularly to a means for receiving messages sent over the simplex or one way Morse telegraph. Very often it is found desirable to attach a temporary supplementary station to such a telegraph line for the purpose of permitting the receiving of all messages transmitted over the line at such supplementary station. My invention aims to provide such a supplementary station which may be attached to the simplex Morse line and will then receive all messages over the line without in any way disturbing the line.

In the drawings the single figure represents two stations of a closed circuit telegraph line showing my invention attached thereto.

Referring to the drawings for a complete description of my invention there are shown two stations, A and B, which are in all respects identical. Accordingly a description of one will suffice to describe both.

The station A is provided with a relay 1 connected to battery 2 through telegraph key 3. This telegraph key is normally shunted by switch 4. The other side of battery 2 is connected to ground at 5, and the other side of relay 1 is connected to the line 6. The relay 1 is provided with an armature 7 normally retracted by spring 8 against a stop 10. Upon energization of the relay 1 the armature 7 is attracted to engage the contact 9. This contact 9 is connected to one terminal of the sounder 11, the other terminal of which is connected to one terminal of battery 12. The other terminal of this battery 12 is connected to the armature 7. The sounder 11 is provided with the usual armature 15 which is normally held retracted by a spring 13 against a stop 14.

The operation of the above described apparatus is as follows:—Normally a current flows from battery 2 at station B through switch 4, relay 1, line 6, relay 1 of station A, switch 4, battery 2 to ground at 5 of station

B through the ground 5 at that station. The relays 1 are normally energized by this current to hold armatures 7 in their raised position against the contacts 9. When it is desired to send a message from either station, the switch 4 at that station is opened to discontinue the current in the relays 1 and permit the armatures 7 to be retracted by the springs 8 and thus terminates the energization of the sounders 11. The key 3 in shunt to the open switch 4 is then depressed by the operator, and at each depression a current flows through the line 6 to energize the relays 1, attract the armatures 7, and thus energize the sounders 11 to indicate the beginning of a signal, while at each release of the key 3 the relays 1 are deenergized to release armature 7 and thus deenergize the sounders 11 to indicate the termination of the signal. The above operation is the usual simplex telegraph line and is well known in the art.

In the system which I have illustrated, the battery is divided between the two stations, as shown. From this it follows that some point between these batteries is of the same potential as the ground, the location of the point depending on the relative battery voltages and on the resistances of the various parts. The point 37 may or may not be this point, but, in any event, the point 37 is normally at a definite potential from ground. When, however, either station opens its switch 4, the point 37 will no longer be at the same potential from ground and the change in potential will cause a current to flow through a circuit, including a condenser, and connected from this point to ground. My invention makes use of this principle.

My invention consists in a wire 16 connected to the line 6 at any desired point 37 through the variable condenser 32 and the variable resistance 33. The other end of this wire 16 is connected to the armatures 19 and 20 of the two polarized relays 17 and 18. The armature 19 normally engages a contact 21 which is connected to one terminal of the relay 18, the other terminal of which is connected to the ground at 27. The armature 20 normally engages a contact 22 which is connected to one terminal of the relay 17, the other terminal of which is connected to ground at 28. The relays 17 and 18 are provided with supplemental contacts 25 and 26.

which are engaged by the armatures 19 and 20 respectively when the armatures are in their abnormal position. These contacts 25 and 26 are connected together and also connected to one terminal of battery 23, the other terminal of which is connected to the sounder 24. The other terminal of this sounder is connected to the wire 16. The sounder 24 is provided with an armature 29 normally retracted by a spring 30 against a stop 31.

The operation of my attachment or supplementary receiving set is as follows:—With both switches 4 in their closed position the potential of the point 37 is at a constant difference from that of the grounds 27 and 28 and no current will flow through relays 17 and 18. Whenever either switch 4, for example that at station A, is open, the polarity of the point 37 will be increased or decreased with respect to that of the grounds 27 and 28. In the present case the potential of the point 37 will increase and accordingly a momentary current will flow from the battery 2 at station B through switch 4, relay 1, line 6, conductor 16, and thence through two paths to ground as follows:—Through armature 19, contact 21, relay 18 to ground at 27, and through armature 20, contact 22, relay 17, to ground at 28. From the grounds 27 and 28 the current will flow back to ground 5 at station B and thence return to battery 2. The current in flowing through relay 17 will traverse this relay in such direction as to tend to move the armature 19 against the contact 21 with which it is already in engagement. Accordingly the armature 19 will not move from its position against the contact 21. In flowing through relay 18 the current will traverse the coil in such direction as to move the armature 20 against the contact 26. This will close a circuit through sounder 24 as follows:—from battery 23 to contact 26, armature 20, line 16, sounder 24, and back to battery 23. This current will attract the armature 29 and indicate the opening of the circuit through line 6. Due to the interposition of the condenser 32 in conductor 16, the current energizing the relay 18 will be but momentary. The relays 17 and 18 are so constructed, however, that their armatures will remain in either extreme position. Accordingly until another impulse comes from conductor 16, the armature 20 will remain in engagement with contact 26 and armature 29 will remain attracted. When, however, the key 3 at station A is depressed, current will again flow through line 6 and relays 1 and the point 37 will return to its original potential with respect to ground. At this time the condenser 32 will discharge to send an impulse through conductor 16 to the point 37 thence to the ground 5 through the two stations in parallel, and thence back

to the condenser through the ground 27, relay 18 and conductor 16. No current can flow, due to this impulse, through the coil of relay 17 since the armature 20 is out of engagement with the contact 22. Accordingly this impulse can have no effect on armature 19. This impulse, however, as has been stated, does flow through relay 18 and flows through the coil thereof in such direction as to return the armature 20 to its normal position against contact 22, and thus open the circuit of sounder 24 to release armature 29 and indicate the termination of the open circuit condition of line 6. Subsequent releases of key 3 will cause attractions of armature 29 and subsequent depressions of key 3 will cause corresponding retractions of armature 29, each retraction of armature 29 indicating the beginning of the transmission of a signal and each attraction of the armature indicating the termination of such signal, the first attraction indicating the opening of the line switch 4 and the final retraction indicating the reclosing of the switch 4. The opening and closing of the switch 4 as thus indicated will indicate the commencement and conclusion of an entire message.

It will be apparent from the above that my supplementary receiving set will receive any message sent from station A to station B by means of the relay 18 through its control of the sounder 24. It will be apparent from the diagram shown in the drawings and from the above description, that the relay 17 will function similarly to control the sounder 24 to receive any message sent from station B to station A. It will also be apparent that inspection of the relays 17 and 18 will indicate which station is sending the message being received by the sounder 24.

It will be apparent that where metallic return is employed, the terminals of the relays 17 and 18 will be connected to this metallic return instead of to ground at 27 and 28, and that this change will in nowise affect the operation of my receiving set. It will also be apparent that my set will operate equally well upon a line employing normally open circuit since the fundamental principle of my invention depends on the change in line potential and this is furnished by the usual open circuit systems as well as by the closed circuit system described. Further, my supplementary set is not affected in its ultimate result when all the line battery is placed at one station. In such a case, while there will normally be a greater difference in potential between points 37 and the grounds 27 and 28, the normally existing potential would still be an intermediate potential, since this potential would still be increased by the opening of the switch 4 at one end and decreased by the opening of the switch 4 at the other end,

and accordingly opening of the circuit at one station will still cause an impulse to flow through my set in one direction while opening the circuit at the other station will 5 cause an impulse to flow in the other direction.

From the above it will be apparent that my supplementary receiving set will operate to receive all messages transmitted over a 10 simplex telegraph line irrespective of the position of the line battery and regardless of whether the circuit is normally closed or normally open. Further it will be apparent that since the fundamental principle of my 15 invention is the utilization of the change of line potential, my supplementary receiving set will operate on any simplex telegraph line where such change in potential occurs.

In the above description I have used the 20 term supplementary receiving set to indicate a receiving set which is attached to an already existing complete telegraph line without disturbance of the line, to receive messages sent over the line. I have used the 25 term simplex as indicating a line from which but one message is transmitted at any one time. I have used the term sounder in a generic sense as indicating any device which will indicate or receive telegraph 30 signals.

While I have here set forth the preferred embodiment of my invention, the modifications herein suggested are considered to be within the scope of my invention, and I also 35 consider as within the scope of my invention all modifications which fall within the scope of the appended claims.

What I claim is:—

1. A supplementary receiving set for a 40 simplex telegraph line, comprising two relays, two sets of normally engaged contacts, one operated by each of said relays, a connection from the line to the coil of each relay through the normally closed contacts of 45 the other relay, respectively, a connection to ground from the other terminal of each coil, two sets of normally open contacts, one operated by each of said relays, connections whereby said normally open contacts are 50 connected in parallel and a sounder circuit connected in series with said parallel connected normally open contacts.

2. A supplementary receiving set for a 55 simplex telegraph line, comprising two relays, two sets of normally engaged contacts, one operated by each of said relays, a connection from the line to the coil of each relay through the normally closed contacts of the other relay, respectively, a connection 60 to ground from the other terminal of each coil, two sets of normally open contacts, one operated by each of said relays, and a sounder circuit controlled by said normally open contacts.

3. A supplementary receiving set for a

simplex telegraph line, comprising two relays, each relay being connected across the line, two sets of contacts, one set controlled by each relay, each set of contacts being interposed in the circuit of the other relay, respectively, two further sets of contacts, one set being controlled by each relay, and a sounder circuit controlled by said two further sets of contacts. 70

4. A supplementary receiving set for a 75 simplex telegraph line, comprising two relays, each relay being responsive to change in line potential, two sets of contacts, one set controlled by each relay, connections whereby each set controls the energization 80 of the other relay, respectively, two further sets of contacts, one set being controlled by each relay, and a sounder circuit controlled by said two further sets of contacts.

5. A supplementary receiving set for a 85 simplex telegraph line, comprising two relays, each relay being responsive to change in line potential, means controlled by each relay for controlling the energization of the other relay, two sets of contacts, one set controlled by each relay, and a sounder circuit controlled by said two sets of contacts. 90

6. A supplementary receiving set for a 95 simplex telegraph line, comprising two relays, each responsive to line conditions, two sets of contacts, one set controlled by each relay and controlling the energization of the other relay, respectively, two further sets of contacts, one set being controlled by each relay, and a sounder circuit controlled by 100 said two further sets of contacts.

7. The combination with a simplex telegraph system comprising a line extending from one station to another station, of a supplementary receiving set comprising two 105 relays, each responsive to line conditions, two sets of contacts, one set controlled by each relay and controlling the energization of the other relay, respectively, and means directly connecting said supplementary receiving set with said line. 110

8. The combination with a simplex telegraph system comprising a line extending from one station to another station, of a supplementary receiving set comprising two 115 relays, each responsive to change in line potential, means controlled by said relays to indicate the message being transmitted, means controlled by said relays to indicate the direction in which said message is being 120 transmitted, and means directly connecting said supplementary receiving set with said line.

9. The combination with a simplex telegraph system comprising a line extending 125 from one station to another station, of a supplementary receiving set comprising two relays, each responsive to line potential, two sets of contacts, one set controlled by each relay and controlling the energization of the 130

other relay, respectively, and means directly connecting said supplementary receiving set with said line.

10. The combination with a simplex telegraph system comprising a line extending from one station to another station, of a supplementary receiving set comprising means responsive to change in line potential for indicating a message transmitted in one direction, means responsive to change in line potential for indicating a message transmitted in the other direction, and means directly connecting said supplementary receiving set with said line.
15. 11. The combination with a simplex telegraph system comprising a line extending from one station to another station, of a supplementary receiving set comprising means responsive to line condition for indicating a message transmitted in one direction, means responsive to line conditions for indicating a message transmitted in the other direction, intermediate means controlled by each responsive means for controlling the other responsive means, respectively, and means directly connecting said supplementary receiving set with said line.
20. 12. The combination with a simplex telegraph system comprising a line extending from one station to another station, of a supplementary receiving set comprising means for indicating the message being transmitted, means responsive to line potential for controlling said indicating means

and for indicating the direction in which 35 said message is being transmitted, and means directly connecting said supplementary receiving set with said line.

13. The combination with a simplex telegraph system comprising a line extending 40 from one station to another station, of a supplementary receiving set comprising means responsive to line potential for indicating a message being transmitted in one direction, means responsive to line potential 45 for indicating a message being transmitted in the other direction, intermediate means controlled by each of said responsive means to control the other responsive means, respectively, and means directly connecting 50 said supplementary receiving set with said line.

14. The combination with a simplex telegraph system comprising a line extending from one station to another station, of a 55 supplementary receiving set comprising means for indicating a message being transmitted over said line, two separate means, each responsive to change in line potential, for controlling said indicating means, two 60 intermediate means, one controlled by each responsive means to control the other responsive means, respectively, and means directly connecting said supplementary receiving set with said line.

In testimony whereof I have affixed my signature.

CHESTER H. TEEGARDEN.
